KNIFE

Torbjorn Evrell, Eskilstuna, and Olle Nordlund, Mjolby,
Sweden, assignors to Eskilstuna Knivfabriks Aktiebolag,
Eskilstuna, Sweden

Filed Jan. 11, 1973, Ser. No. 322,785

Term of patent 14 years

Int. Cl. D8—03

U.S. Cl. D8—99

FIG. 1 is a side elevation of a knife showing our new design;

FIG. 2 is a top plan view thereof;

FIG. 3 is a bottom plan view thereof;

FIG. 4 is a view from one end thereof;

FIG. 5 is a view from the other end thereof; and,

FIG. 6 is a side view of the side opposite that shown in FIG. 1 illustrating the blade of the knife in open position.

We claim:

The ornamental design for a knife, substantially as shown.
